SIPHON BOTTLE HEAD

Harry J. Scott, San Francisco, Calif.

Application May 13, 1935, Serial No. 21,076

5 Claims. (Cl. 215—5)

This invention relates to a cap or head for siphon bottles, which bottles are also known as "Seltzer" bottles and are commonly used as containers for carbonated liquid or "Seltzer" water 5 or the like in which gas released from the liquid forces the liquid through the head upon opening a valve that is included in the head.

The objects of the invention are to provide a construction for a siphon bottle head whereby 10 any metal suitable for casting may be used for the body of the head, and also to provide a valve arrangement that will permit filling the bottle with liquid and ejecting it therethrough without unnecessary loss of gas from the liquid, and which 15 valve construction insures against leakage over a long period of hard usage. Other objects and advantages will appear in the drawing and specifications.

In the drawing, Fig. 1 is a plan view of my improved siphon bottle head.

Fig. 2 is a vertical sectional view of Fig. 1 with a portion of the bottle shown in section.

Fig. 3 is a bottom plan view of the head.

Fig. 4 is a bottom plan view of the main body 25 portion of the head without the internal parts and handle.

Fig. 5 is a sectional view of the removable conduit of my improved head.

Fig. 6 is a sectional view of Fig. 5, taken along 30 the line 6—6 thereof.

Fig. 7 shows two parts of the valve operating means that are adapted to be connected when in operating position in the head body.

Fig. 8 is a perspective view of one of the internal parts of the head.

Fig. 9 is a perspective view of the valve operating lever.

Heretofore, siphon bottle heads have generally been constructed from a special and expensive 40 tin alloy to insure against objectionable effects of the liquid ordinarily used in siphon bottles. I have overcome the necessity for using such metals by a specially constructed liquid conduit of cheap material, such as rubber, which is impervious to the action of the liquid and which does not in any way affect the taste of the liquid that has passed therethrough.

In previous siphon bottle heads it has been customary to use disk or plug valves either with 50 or without a rubber seating surface for engagement against a metal valve seat. In operation in a siphon bottle head the use of such valves results in violently breaking up the liquid in passing the valve, with consequent loss of a material 55 amount of the gas. Since siphon bottles are also

filled through their heads, the same loss of gas occurs as when the liquid is discharged through the head, and for the same reason. Ordinarily the liquid is now charged with considerably more gas than is necessary prior to injecting it into 5 the bottles in order to insure a sufficient gas content in the liquid when it is in the bottle to compensate for the gas that is lost in filling the bottles. With my invention, there is practically no loss of gas in filling the bottle although the 10 same filling process is used due to my improved valve construction that permits an absolutely free flow of the liquid into the bottles without breaking up the liquid. Also in closing the valve, a soft rubber to rubber seat is effected that insures 15 against leakage, irrespective of minor variations, and there is practically no wear whatsoever at the point of sealing.

In detail my improved siphon bottle head comprises a main body portion 1 of any metal suitable for casting, which body portion is generally T-shaped, the vertical leg 2 being recessed at 2' and interiorly threaded to threadedly engage over the neck 3 of an ordinary siphon bottle. The cross arm of the body is provided at one end 25 with a horizontally extending outwardly opening recess 4 of elliptical cross section and the opposite end of the cross arm is formed to provide a generally downwardly extending discharge nozzle or spout 5 with a bore 6 therethrough opening at its inner end into a recess 7 that communicates with the upper end of the recess 2'. A vertical wall 8 disposed within the recess arm of the body and slightly to one side of the vertical axis of the body forms a partition between 30 the inner end of recess 4 and recess 7, and a portion 9 of the lower wall of recess 4 extends across a portion of the recess 2' and connects with the lower edge of partition wall 8, the bottom surface of this portion 9 being horizontal 35 and flat.

The inner opposite sides of recess 7 adjacent its juncture with recess 2' are shouldered at 10 (Fig. 4) to provide horizontal, flat, downwardly facing surfaces extending longitudinally of the cross arm from opposite ends of the wall 8, and the portion 9 is cut away at its opposite edges as at 11 to provide a slight continuation of the shoulder 10. Against this shoulder 10 is seated a removable semi-annular flat piece 12 (Figs. 2, 50 8) the lower flat side of said piece being flush with the lower flat side of the portion 9 that extends over recess 2', thus forming with the portion 9 an annular flat seat around the upper end of recess 2'. 55

The conduit through said body comprises a rubber tube molded to provide a horizontally extending tubular portion 13 turned downwardly at one end to provide a vertical tubular portion 14, and the lower end of the portion 14 is outwardly flanged at 15 to provide a circular disk of an outer diameter adapted to firmly seat around upper margin against the flat surface formed by member 12 and portion 9. The conduit including the flange 15 is shown in Fig. 5 before it is inserted into the head, and is made in the manner there shown for the purpose of facilitating the molding operation.

When positioned within the body of the siphon head, the portion 13 of the conduit is fished through the bore 6 of the arm 5 from the inside by means of any suitable instrument, such as a wire with a clamp at one end (not shown) although it may easily be inserted by use of the fingers of the hand. When in the bore 6, the outer end of the conduit terminates adjacent the outer end of bore 6, the inner side of the outer end of said bore being slightly tapered outwardly. A short tapered sleeve 16 is inserted in the outer open end of the conduit, which sleeve has an outwardly projecting flange 17 around its outer end adapted to extend over the outer end of nozzle or spout 5, and annular cap 18 centrally apertured about the size of the inner decimeter of sleeve 16 with an inwardly turned flange 19 defining the edge of the aperture is adapted to threadedly engage threads 20 on the outer side of the nozzle 5 at its outer end. When cap 18 is screwed onto the nozzle the sleeve 16 is in the nozzle, compressing the end of the conduit 13 between the tapered inner side of the bore 6 and outer tapered side of sleeve 16, thus securing the conduit to the nozzle at its outer end. The inner bore of sleeve 16 and the bore of the rubber conduit are substantially flush as shown in Fig. 2, thus presenting a continuous smooth passageway through the nozzle and to the inner opening of the conduit that opens downwardly about the center of the head in axial alignment with the vertical axis 45 of the bottle. Cap 18 and sleeve 16 are of special tin alloy as ordinarily used in siphon bottles, or it may be of any suitable metal impervious to action of the liquid and which do not affect the liquid. Likewise conduit 13, 14 and flange 15 may be of any suitable flexible material suitable for use with carbonated liquids, although I have found rubber to be most satisfactory.

The control of flow of the fluid is by a roller 20 positioned within recess 7 and extending transversely across the portion 14 of the conduit on the side thereof opposite wall 8. The portion 14 of the conduit is preferably formed flat along the side adjacent wall 8 and is horizontally elongated in cross section, as best seen in Fig. 6, the side opposite wall 8 of the portion 14 being rounded as shown in the drawing. Of course it may be elliptical, but for best results I prefer the form as shown. The walls of the portion 14 of the conduit are preferably thicker than the walls of the portion 13, as shown in Fig. 5. In Fig. 2 the walls are indicated in compressed position.

The roller 20 is supported in the head in the position described, on spaced horizontal arms 21 (see Fig. 7). These arms extend through spaced rectangular openings 22 in the wall 8 transversely across the portion 14 of the rubber conduit and are slotted as at 23 with vertical openings 24 at the ends of the slots for receiving the stub shafts 25 at the opposite ends of the roller 20. The arms 75 are connected at their ends opposite the slots by

an elliptical disk or cross bar 26 that is adapted to slidably fit in the recess 4. The outer side of bar 26 has a semi-cylindrical, horizontally-elongated projection 27 thereon adapted to fit in a similarly shaped recess 28 in the upper end of a generally downwardly extending lever 29 when the bar 26 is in the recess 4, the upper end of said lever being provided with a semi-cylindrical, horizontally-extending projection 31 adapted to fit in a similarly formed downwardly opening recess 32 formed in an extension 31' of the top of the body of the siphon head.

In installing the roller and its operating parts, a coil spring 33 is first slipped over each arm 21, the arms are then inserted into the recess 4 and through openings 22 in wall 8 and the spring is compressed by forcing cross bar 26 into recess 4 until the open ends 24 of slots 23 clear the side of the portion 14 of the rubber conduit opposite the side of said portion that is adjacent wall 8. A side of flange 15 is pulled down to permit insertion of the roller 20 to above the arms 21 when the stub shafts 25 of the roller will drop through the openings 24 of arms 21 into slot 23.

The projection 31 of the lever 29 is then inserted in recess 32 and upon releasing the pressure on cross bar 26 the projection 27 will enter recess 28 in the lever and the end 32' of the body of the siphon head will engage against a shoulder 35 of the lever 29, thus retaining the lever 30 against separation from the head and retaining all parts in assembled relation with the roller 20 tightly squeezing the portion 14 of the rubber conduit together to seal it against leakage past this point.

The head is then screwed onto the neck 3 of the siphon bottle and flange 15 of the conduit acts as a washer against flange 36 that is secured to the upper end of glass tube 37 through which the liquid is forced by gas pressure within the bottle. The axis of the bore of tube 37 is in alignment directly below the lower open end of the portion 14 of the rubber conduit in the siphon head and upon pressing downwardly on lever 29 the portion 14 is opened and the liquid will pass directly into the conduit and therethrough and out of nozzle 5 without any sharp corners or any obstacles or projections in the passageway to cause breaking up of the liquid and consequent loss of gas. Obviously, in filling the bottle through the nozzle, the same smooth flow of liquid into the bottle will result.

The device of this invention has in actual use resulted in the delivery of an appreciably higher charged liquid than is possible in any devices of which I am aware, and the liquid may be kept in the bottle indefinitely without loss of gas due to the absolute seal of the conduit at the point of the roller. Also liquid of a much lower gas content may be injected into the bottle through my nozzle for obtaining the desired character of liquid in the container since it is not necessary to use the highly charged liquids now employed in order to compensate for loss of gas in the nozzle.

Having described my invention, I claim:

1. A siphon bottle head comprising a cast metal body formed with a hollow, vertical cylindrical portion adapted to engage over the neck of a siphon bottle at its lower end and a laterally directed discharge nozzle at its upper end with the inner end of the bore of said nozzle connecting directly with the inside of said hollow cylindrical portion; a horizontal, annular, downwardly facing seat below the inner end of the bore of said nozzle; a flexible conduit supported within said head

provided with a horizontal, outwardly directed, flange at one end adapted to fit against said downwardly facing seat and the opposite end of the conduit extending into the bore of said nozzle, and means above said flange accessible from outside the body for opening and closing said conduit to flow of liquid therethrough.

2. A siphon bottle head comprising a metal body having an outwardly opening downwardly directed recess therein for receiving the outlet end of the neck of a siphon bottle and formed with a laterally projecting nozzle member having a through bore communicating between said recess and outer end of the nozzle member, a flexible rubber conduit extending substantially from end to end of said bore supported against the walls thereof, said conduit projectioned into the recess at its inner end, means for fixedly securing said conduit within said bore against displacement therein and spring actuated valve means within said recess normally forcing the walls of the conduit together to close the conduit to flow of fluid therethrough.

3. A siphon bottle head comprising a body formed with an outwardly opening recess therein at one side and provided with a laterally extending nozzle member having a bore therethrough communicating at its inner end with said recess, a flexible fluid conduit of rubber within the bore of the nozzle member extending from the outer end of the nozzle member to within said recess, means at the outer end of the nozzle member securing one end of the flexible conduit thereto and a spring urged valve member within said recess

arranged and adapted for normally forcing the walls of the fluid conduit together to close the conduit against flow of fluid therethrough.

4. In a construction as defined in claim 3 said valve member comprising an elongated horizontally extending element formed to force the walls of the conduit together along a straight line extending the full width of the conduit and a valve lever mounted at one side of the siphon head operatively connected to said element for moving the element to release its pressure against the walls of the conduit and to open the conduit to flow of liquid therethrough.

5. A siphon head comprising a body formed with an outwardly opening vertical recess on the lower side adapted for receiving therein the upper end of the neck of a siphon bottle, a laterally and downwardly extending nozzle member projecting from a side of the body having a through bore extending from the outer end of the nozzle member to said recess, a continuous open ended flexible conduit extending from the outer end of the bore of the nozzle member to within the aforesaid recess, said conduit being formed with an outwardly directed flange at the end within the recess for engaging the edges of the siphon bottle neck at its mouth, means at the outer end of the nozzle member securing the outer end of said conduit thereto and a spring urged valve member within said recess arranged and adapted to normally force the walls of the conduit together for closing the conduit against flow of fluid therethrough.

HARRY J. SCOTT.
